UNITED STATES PATENT OFFICE.

JOHN W. BECK, OF WASHINGTON, PENNSYLVANIA.

SUPPLEMENTAL SOLE FOR SHOES.

1,292,681.

Specification of Letters Patent. Patented Jan. 28, 1919.

Application filed August 16, 1917. Serial No. 186,441.

To all whom it may concern:

Be it known that I, JOHN W. BECK, a citizen of the United States, residing at Washington, in the county of Washington and 5 State of Pennsylvania, have invented certain new and useful Improvements in Supplemental Soles for Shoes; and I do hereby declare the following to be a full, clear, and exact description of the invention, such as 10 will enable others skilled in the art to which it appertains to make and use the same.

My invention relates to a new and useful supplemental sole for shoes and is primarily designed for use upon the soles of shoes of 15 persons walking in mines, mills, foundries, tin shops and factories, quarries, and all such occupations wherein the boots or shoes of the operators are subjected to very great wear, danger of puncture, and the like, and 20 is an improvement of my former Patent Number 639,651, granted to me December 19, 1899.

One of the aims of the present invention is to provide a supplemental sole of an exceedingly 25 flexible nature, provided with means for efficiently securing the same upon the sole of an ordinary boot or shoe in such a manner as to render it practically impossible to tear the supplemental sole from the 30 shoe sole by its contact with obstructions upon a surface, or by the entering of sharp pieces of metal between the supplemental sole and the ordinary sole and resulting in either cutting the securing members or prying 35 the supplemental sole from the ordinary sole.

Another aim of my invention is to provide 40 the supplemental sole with a novel form of carks which not only provide efficient anti-slipping members but also provides efficient protective members for the screws, nails, or other desirable securing means, employed for maintaining the supplemental sole in 45 operative position upon the sole of the boot or shoe.

A further aim of my invention is to produce a flexible supplemental sole constructed of flexible material and grooved or scored in a manner to divide the sole into sectors 50 which are maintained in assembled relation by a thin connecting strip at the bottom of the scores or grooves until the supplemental sole is applied to the sole of a shoe, whereby the thin connecting strips will become ruptured by the bending of the sole thereby separating the respective sectors from each

other and adding to the flexibility of the supplemental sole and ease of comfort to the wearer of the boot or shoe.

A further aim of my invention is to provide 60 the supplemental sole with members for engaging the edges of the forward portion of the shoe sole to provide guard members to prevent the introduction of foreign matter between the supplemental sole and 65 the shoe sole and at the same time the members providing additional means for securing the supplemental sole upon the shoe sole.

A further aim of my invention is to provide 70 means for efficiently protecting the toe proper of a boot or shoe and at points most likely to be punctured and thereby endanger the foot of the wearer.

A still further aim of my invention is to produce 75 a supplemental sole for the boots and shoes of mill workers and the like, which is simple in construction, efficient and durable in use, readily applied to the ordinary boot or shoe and which can be manufactured and sold upon the market at a 80 nominal cost.

These and other objects and advantages of my invention will more fully appear as the nature of the invention is more clearly understood from the following specification, 85 the subject matter of the claims, and the several views illustrated in the accompanying drawings, in which:

Figure 1 is a bottom plan view of the supplemental sole in its complete form. 90

Fig. 2 is a fragmentary side view of the front portion of a shoe, showing the supplemental sole in operative secured position thereon.

Fig. 3 is a vertical transverse sectional view, on line 3—3 of Fig. 2 and looking in the direction of the arrow, showing the detail construction of the supplemental sole and the means for securing the same upon the shoe sole. 95

Fig. 4 is a vertical sectional view through one of the hollow carks employed with one of the securing screws projecting therethrough. 100

Fig. 5 is a fragmentary side view of the front portion of a shoe, showing the supplemental sole secured thereon and the toe protector or guard member employed in conjunction therewith. 105

Referring to the drawings, wherein similar reference characters denote corresponding parts throughout the several views, 110

denotes the forward portion of a boot or shoe and 2 the leather sole thereof.

The base 3 of the supplemental sole which I employ may be formed of any suitable 5 alloy, metal or composition, but is preferably constructed of flexible steel and may be formed of any suitable and desired size and shape and has formed in its under surface the plurality of substantially V-shaped 10 transverse grooves 4, and a central longitudinally extending substantially V-shaped groove 5. The groove 5 intersects and extends from the rearmost transverse groove 4 to the foremost transverse groove and 15 intersects and crosses the intermediate transverse grooves 4. By this manner of grooving the under surface of the base 3 of the sole, the sole is divided into sectors providing a toe member, a rear member, and 20 a plurality of intermediate members. The transverse grooves 4 and the longitudinal groove 5 are cut or otherwise formed of a sufficient depth to almost entirely penetrate through the base plate 3 of the sole, but just 25 far enough to provide or leave a thin connecting strip between the respective sectors for efficiently maintaining the sectors in assembled relation to facilitate the ready handling of the supplemental soles when 30 packing, shipping or offering the soles for sale upon the market.

Formed upon the outer edge of the sector constituting the toe piece of the sole is the upwardly extending flange member 6, and 35 also formed upon the outer ends of preferably half of the intermediate sectors are the upstanding flanges 7. The flange 6 and the flanges 7 are preferably formed of malleable iron so that the flange 6 and the flanges 7 40 may be bent inwardly by any suitable means for impinging the outer edge of the shoe sole. The flange 6 and flanges 7 are provided with any suitable number of apertures through which and into the shoe sole 45 are projected the securing screws 8, or other suitable securing means, to assist in securing the supplemental sole upon the shoe sole and to provide guard members therefor, and in order to prevent foreign material, such 50 as sharp pieces of tin, steel, or other metal, from passing between the meeting edges of the respective flanges 6 and 7 I preferably form the forward edges of the flanges 7 with the projections 9, indicated by dotted 55 lines in Fig. 2, and in a manner that the projections 9 will underlie the contiguous rear edges of the respective flange 6 and flanges 7.

Within the base plate 3 of the supplemental sole are formed a plurality of apertures 10 through which the main securing screws 11, or other suitable securing means, pass and into the shoe sole 2 for securing the supplemental sole upon the shoe sole in 65 addition to the impinging action of the

flanges 6 and 7 and the screws 8. The screws 11 constitute the primary securing members for the supplemental sole, and each of the screws 11 before being projected through the base plate 3 are passed through 70 the countersunk opening 12 of the hollow semispherical calks 13 with the head 14 of the respective screws seated within the countersunk opening 12 of the calks 13, whereby the screws 11 not only secures the 75 base plate 3 of the supplemental sole upon the shoe sole 2, but also secures the respective calks 13 in secure operative position upon the under surface of the base 3 of the supplemental sole.

The hollow calks 13 that I employ are preferably formed semi-spherical as shown, though the calks may be formed rectangular, triangular or other conformations in cross section and of any suitable material, 85 but the calks are preferably formed of hardened steel to provide against the excessive wear to which these calks are constantly subjected when in use in mills, factories, etc., so as to prolong the life of the calks 13, 90 as well as the usefulness of the supplemental sole. The calks 13 are not employed as vacuum cups in the manner that the rubber vacuum cups of a majority of the supplemental soles now upon the market are employed, but are provided and have a three fold function in that, the calks 13 not only provide efficient anti-slip members to prevent the wearer from slipping when walking over surface strewn with cut and broken metal, tin, or the like, but also being of an exceedingly hard metal will wear for a long time and thus prevent excessive wear upon the under surface of the base plate 3 of the supplemental sole, and at the same 105 time will form an efficient protection to and prevent wear of the heads 14 of the main securing screws 11, so that, by the preservation of the heads 14 of the main securing screws 11, or the heads of any other securing means which may be employed, it is practically impossible to wrench or otherwise dislodge the supplemental sole from the shoe sole as the heads of the securing members are free from wear and their function as securing members unimpaired.

To protect the toe portion proper of the boot or shoe, the toe protector or guard cap or member 15 is provided and formed of any suitable material and shape to cover the toe of the boot or shoe and in suitable spaced relation thereto, and may have its rear edge extended as far back upon the boot or shoe as desired. The lower edge of the protector 15 is provided with a plurality of apertures 120 for registering with the apertures of the flange 6 of the toe member of the supplemental shoe sole and for receiving the screws 8 for securing the protector 15 and the flange 6 upon the boot or shoe sole 2. The pro- 125

tector 15 has been shown as a separate member from the supplemental sole, but this protector may be formed integral with the toe member of the supplemental sole by forming 5 the flange 6 and the protector 15 in one piece or in other words by uniting the lower edge of the protector 15 and the edges of the toe member of the supplemental sole and extending the rear edge of the protector 15 as 10 far rearwardly as desired.

While I have shown and described only a portion of the sectors provided with the guard flanges 6 and 7 I may, however, supply 15 the remaining sectors with like flanges if deemed necessary, but as the toe of the shoe sole and the adjacent side edges of the shoe sole are the portions most likely to come in contact with dangerous obstructions which may have accumulated upon the floor, 20 ground, or other surface, the provision of the guard flanges or members as herein shown and described will be sufficient for ordinary purposes; and again, my invention is not to be understood as being restricted 25 to the production of a supplemental sole only, as I may construct heel plates for the boots or shoes of workmen which will be constructed in a similar manner that my supplemental shoe sole is constructed, the 30 only difference, of course, being in the conformation of the heel plate from that of the supplemental sole.

The supplemental sole may be made and sold upon the market without the anti-slipping 35 members, if desired, to provide a sole with a plane surface to meet the needs of workmen not requiring the anti-slipping members.

While I have herein shown the preferred 40 embodiment of my invention I may resort

to variations and alterations in the general conformation and construction thereof to meet the exigencies of the case without departing from the spirit of the invention or the scope of the claim. 45

Having described my invention, what I claim as new and desire to secure by Letters Patent, is:

A supplemental shoe sole, comprising a metal plate provided with transverse 50 grooves and a longitudinal groove intersecting said transverse grooves to divide said plate into a plurality of sectors, the respective grooves being of a depth to provide a thin flexible connecting strip between said 55 sectors, said sectors being provided with a plurality of apertures, apertured guard flanges upon the edges of the front sector and certain of the adjacent intermediate sectors, overlapping members upon the meeting 60 edges of said guard flanges to provide closed joints thereat and to provide for the relative movements of said sectors and said guard flanges upon the bending of the main shoe sole, screws projecting through the 65 apertures of said sectors and the apertures of said guard flanges for securing said supplemental shoe sole upon the bottom and edges of said main shoe sole, and anti-slipping wear members secured upon the bottom 70 surfaces of said sectors by the securing screws projecting through said apertured sectors.

In testimony whereof I have signed my name to this specification in the presence of 75 two subscribing witnesses.

JOHN W. BECK.
